OSCAR POTTER, OF DOWNERS GROVE, ILLINOIS, ASSIGNOR OF ONE-HALF TO
GEORGE M. BARD

SMELTER

Application filed February 18, 1929, Serial No. 340,801. Renewed October 6, 1930.

The object of my invention is to produce a smelter of simple construction by means of which iron ore, and other ores, may be smelted with a minimum expenditure and waste of 5 fuel.

The accompanying drawing is a vertical sectional perspective of an embodiment of my invention.

In the drawing 10, 10 indicate the side walls 10 and 11 one of two end walls forming the smelting chamber, said walls preferably inclining inwardly and upwardly in order to prevent "hanging" of material in the chamber. The chamber formed by walls 10 and 11 is closed 15 by a cover arch 12 preferably with charging holes 13 and closures 14 therefor.

A short distance above the floor 15 of the smelting chamber the side walls are perforated with a series of passages 16 leading to 20 a chimney duct 17 formed between the outer face of wall 10 and a parallel wall 18. Paralleling wall 18 is a wall 19 which, with wall 18 forms an air supply duct 20 the upper end of which is connected by pipe 21 to a suitable 25 source of air blast.

Leading from the lower end of duct 20 are several ducts or tuyères 22, conveniently an inverted channel shaped passage of fire brick, extending across the chimney and into and 30 through perforations 16 so that their discharge ends are presented into the smelting chamber. These ducts or tuyères are considerably smaller, in cross-section than perforations 16 so as to leave ample areas for outlet 35 of combustion gases from the smelting chamber. Tap holes 25 are provided for draining the smelting chamber.

In operation the smelting chamber will be initially heated by a suitable fire stimulated 40 by blasts through tuyères 22. Thereupon a bed of fuel is formed and upon this bed is charged a mixture of fuel, flux and ore to be smelted and air blasts established through the tuyères into the smelting chamber. The top 45 of this chamber will be kept closed and all outlet of gases from the chamber will be through passages 16 into chimneys 17. These chimneys may be equipped with suitable dampers.

50 I claim as my invention.

1. A smelting furnace comprising a main chamber formed by bounding walls and a normally closed top, a chimney duct formed alongside one of said walls, an air supply duct formed alongside the chimney duct and subject to the heating influence of the burning gases passing through said chimney duct, and tuyères leading from the air duct across the chimney duct to the smelting chamber, and ducts connecting the smelting chamber and 55 chimney.

2. A smelting furnace comprising a main chamber formed by bounding walls and a normally closed top, a chimney duct formed alongside one of said walls, an air supply duct 60 formed alongside the chimney duct, and tuyères leading from the air duct across the chimney duct to the smelting chamber, and ducts connecting the smelting chamber and chimney, said ducts being of larger cross-sectional area than the tuyères and said tuyères lying therein.

In witness whereof, I, OSCAR POTTER, have hereunto set my hand at Downers Grove, Illinois, this twelfth day of February, A. D. 75 one thousand nine hundred and twenty-nine.

OSCAR POTTER.
